UNITED STATES PATENT OFFICE.

CHARLES KERR, OF CHICAGO, ILLINOIS.

POWER PRESS.

Application filed August 10, 1925. Serial No. 49,443.

My invention relates to power presses, designed to compress fluid yielding substances and to extract the fluid therefrom, and the main object of my invention is the provision 5 of an improved machine of this character which will be automatic and continuous in operation, and which will embody certain desired features of simplicity, efficiency and convenience.

One of the important objects of my invention is the provision of a power press having a continuous conveyor for receiving the liquid yielding material, for conveying the material during the pressing operations and for discharging the residue after the pressing operations. Further objects are to provide 15 means for forming the conveyor into a trough-like carrier just prior to the feeding thereon of the material to be pressed, to provide means for closing the trough-like formation during the pressing operations, and to provide means for spraying water or other suitable solvent on the material during the pressing operations.

Other objects will appear hereinafter.

The invention consists in the combinations and arrangements of parts hereinafter described and claimed.

The invention will be best understood by reference to the accompanying drawings, forming a part of this specification, and in which,

Figs. 1 and 2 represent side elevational views of my improved machine, the view shown in Fig. 1 representing the front portion of the machine while that shown in Fig. 2 represents the rear portion thereof;

Fig. 3 is a top plan view of the machine;

Fig. 4 is a cross section taken approximately on the line 4—4 of Fig. 1;

Fig. 5 is a cross section taken approximately on the line 5—5 of Fig. 2;

Fig. 6 shows another cross section taken approximately on the line 6—6 of Fig. 2;

Fig. 7 represents a vertical sectional view, taken centrally and longitudinally of the machine on the line 7—7 of Fig. 3;

Fig. 8 represents a longitudinal section through the former device and the ejector device, along with associated parts, this view being taken approximately on the line 8—8 of Fig. 3;

Fig. 9 is a detail view of the means for levelling material in the conveyor, this view being taken on the line 9—9 of Fig. 8; and

Fig. 10 is a section taken on the line 10—10 of Fig. 8.

With more particular reference to the accompanying drawings, wherein I have illustrated the preferred embodiment of my improved machine, it will be seen that I provide a skeleton frame made of angle bars and consisting of parallelly arranged bars 11—11, which are connected by the various devices and parts hereinafter to be described and which are supported upon suitably disposed leg members 12. Arranged upon the forward portion of the machine is a hopper 13 (Figs. 1 and 3) which is supported upon the top bars 11—11 by means of a suitable hopper supporting frame 14. Associated with the hopper and hopper supporting frame at the forward end thereof is a reinforcing member 15, and at the rear end thereof, a bearing bracket 16; it being observed that the hopper is supported in such manner that its delivery opening 17 extends longitudinally of the machine and centrally thereof. Suitably associated with the hopper delivery opening 17 is a material feed screw 18 whose axis is suitably journalled at one end in the hopper supporting frame and reinforcing member 15 and at the other end in the hopper supporting frame and bearing bracket 16.

As will be understood from an inspection of Figs. 1, 2 and 3, there are operatively arranged upon the frame work, rearwardly of the hopper, two pairs or sets of pressing units, which are denoted in general by the reference numerals 19—20 and 21—22, it being observed in this connection that the pressing units 19 and 21 constitute top units since they are arranged over the respective cooperating units 20 and 22.

Inasmuch as the top pressing units 19 and 21 are substantially alike in their construction, a detailed description of one will, it is thought, suffice for both. The top pressing unit 21 (see Figs. 2, 6 and 7) comprises two shafts 23—23 whose opposite ends are journalled in bearing blocks 24 slidably mounted in inverted U-shaped guide frames 25 which are bolted upon and rise from the top bars 11—11. Also slidably mounted in the guide frame 25 are pressure blocks 26 into which are threaded the ends of adjustment screws 27 operatively held in bosses 28 at the tops of the guide frames. Between the pressure blocks 26 and bearing blocks 24 are interposed spiral springs 29. Surrounding and

connecting the shafts 23—23 are a plurality of bearing bridges 30; and secured upon these shafts in positions between the bearing bridges 30 are sprocket wheels 31. Connecting the sprocket wheels 31 of one shaft with the sprocket wheels 31 of the other shaft are sprocket chains 32 upon which are secured cross strips 33. The sprocket wheels, sprocket chains and cross strips thus arranged, comprise a continuous pressing element which is referred to in general by the reference numeral 34. The continuous pressing element 34 travels around the bearing bridges 30 and is suitably and effectively supported thereby during pressing action. From what has been said it will be obvious that the top pressing unit 21 may be adjusted relatively to the bottom pressing unit 22.

The rear shaft 23 of the pressing unit 21 constitutes, in the present construction, the main driving shaft for the machine, the same being provided with a large driving gear 35 which meshes with pinion 36 on the driving shaft 37 of motor 38 which is suitably mounted on a bed plate 39. In the construction herein exemplified, the bed plate 39, carrying the motor, is adjustably mounted upon a platform 40 securely arranged and positioned upon the rear legs 12 of the machine. Any suitable means for adjusting the bed plate of the motor may be provided but as herein shown, the adjusting means comprises the provision of elongated slots 41 provided in the platform 40 for the adjustment of the securing bolts 42 which are employed for connecting the bed plate with the platform. Provision is thus made for adjusting the position of the motor in order suitably to compensate for the up-and-down adjustment of the pressing unit 21; but it will be understood any suitable and adjustable driving means may if desired be employed between the motor shaft 37 and the pressing unit driving shaft 23. The bottom pressing unit 22 is composed of two shafts 43 and 44, the shaft 43 being journaled in bearings 45 secured upon side bars 46 suitably provided for the purpose between adjacent supporting legs 12. The other shaft 44 is journaled in bearings 47 which are adjustably mounted upon the side bars 46, the means of adjustment consisting in providing said bars with elongated slots 48 for the suitable adjustment of the securing bolts 49. Provision is thus made for adjusting the shaft 44 toward and away from the shaft 43; and means for effecting this adjustment is provided in the form of adjusting screws 50 which are suitably tapped through leg members 12 and reinforcing members 51 thereon, the free extremities of these adjusting screws being threaded into extensions 52 of the bearings 47. This bottom pressing unit 22 is provided with a pressing element 53 which is composed of sprocket gears, sprocket chains and cross strips, all precisely like the pressing

element 34 of the top pressing unit. For the suitable backing of the upper run of the continuous pressing element 53 of the bottom pressing unit 22, I provide bearing bridges 54 which are supported upon cross bars 55, there being adjusting screws 56 threaded through the side bars 46 and bosses 57 thereon for the support of the cross bars 55. Arranged in the pressing unit 22 just below the bearing bridges 54 is a catch basin 58 for receiving the liquids extracted from the materials drawn between the continuous pressing element 34 of the top pressing unit and the continuous pressing element 53 of the bottom pressing unit. The pressing units 19 and 20 are constructed substantially like the pressing units 21 and 22. The top pressing unit 19 has a continuous pressing element 59 which operates with a similar pressing element 60 upon the bottom pressing unit 20. A catch basin 61 is also provided within the bottom pressing unit 20 to receive the liquids extracted from the materials drawn between the pressing elements 59 and 60.

The rear or driving shaft 62 of the top pressing unit 19 is operated from the main driving shaft 23 by means of a sprocket chain 63 which connects a sprocket gear 64 upon said main shaft 23 with a sprocket gear 65 upon the shaft 62. The main driving shaft 23 also carries a gear 66 which meshes with a gear 67 upon the shaft 43 of the pressing unit 22, whereby the continuous pressing element 53 is operated. In a similar manner the rear shafts of the top and bottom pressing units 19 and 20 are provided with meshed gears 68 and 69, whereby the bottom pressing unit is operated. In the present exemplification, the feed screw 18 is driven from the rear shaft 62 of the top pressing unit 19. To this end, the shaft 62 carries a sprocket gear 70 with which is engaged a sprocket chain 71 extending to a sprocket gear 72 arranged on stud shaft 73 suitably mounted upon the frame work and in bearing bracket 16 upon the hopper. Stud shaft 73 carries a gear 74 which is engaged with a worm 75 carried by the axis of the screw 18. The material delivering screw 18 is thus operated in conjunction with the operation of the two pairs of pressing units.

For conveying the liquid yielding material I provide a continuous or endless conveyor 76 which is mounted to travel longitudinally of the machine and to be drawn successively between the two pairs of pressing units 19—20 and 21—22. To this end the continuous conveyor 76 is passed between the continuous pressing elements 59 and 60, of the pressing units 19—20 and then between the continuous pressing elements 34 and 53 of the pressing units 21—22; and thence it is returned under the bottom pressing units 22 and 20 and subsequently is trained over idler pulleys 77 and 78 to the top of the machine at the front thereof (Figs. 1 and 2) from which position it

passes underneath the feed screw 18 where it receives the material to be pressed.

According to an important feature of my invention, the conveyor 76, consisting of canvas or other suitable material, is, prior to receiving its lading, made trough-like in shape by means of a former device located forwardly of the hopper 13. This former device, as best illustrated in Figs. 1, 4 and 8, comprises a conveyor slideway 79 having insloping sides 80, the said slideway 79 narrowing toward the rear of the machine while the insloping sides progressively increase in height. Depending from a suitable support 81 arranged upon the top bars 11-11, is the former device 82 which like the slideway 79 narrows in a direction towards the rear of a machine and which has insloping sides 83 in substantial agreement with the insloping sides 80, it being observed from an inspection of Fig. 4 that these parts are so arranged that the former proper 82 occupies a position within the former casing 79 and insloping sides 80. Continuous conveyor 76 in being drawn through the former, thus constructed, is made trough-like in shape, having insloping sides 84 adapted to retain the material to be pressed. As the conveyor with its insloping sides 84 advances towards the pressing units 59-60 it is met by a continuous closure band 85 which is trained around the pressing unit 59 and also around an idler pulley 86, in such manner as to travel in the direction of the conveyor and to contact with the insloping sides 84 thereof forcing the same downwardly upon the conveyed material and closing the interstice or open space between the confronting edges of the insloping conveyor sides 84. In this manner the material in the conveyor is completely covered or enveloped so that it cannot escape during the pressing operations. In a similar manner a continuous closure belt 87 is arranged around the top pressing unit 21 and around a pulley 88, so that when the conveyor is drawn between the pressing elements 34 and 53 of the pressing units 21 and 22 the conveyor material will again be enclosed against escape during the pressing operation. In Figs. 1 and 2 it will be observed that the idler pulleys 86 and 88 are mounted in suitable bearing blocks 89 adjustably mounted upon the supporting frame and adapted to be adjusted by means of adjusting screws 90.

Suitably arranged upon leg supported rails 91, is a combination ejector and spreader 92 which is formed, as best shown in Figs. 4 and 8 so as to serve as a scraper for scraping off the material adhering to the conveyor 76 and further to spread out and flatten the insloping sides 84 of the conveyor, preparatory to the travel of the conveyor over the idler pulley 78. Just prior to the passing of the conveyor over said idler pulley 78, the conveyor is further operated on by a rotary brush 93 held upon brackets 94 located on

the side rails 91. This rotary brush is driven by means of the following driving elements: gear 95 arranged on its axis, gear 96 arranged on an axis 97, a sprocket wheel 98 arranged upon the axis 97 and a sprocket chain 99 which extends to a sprocket gear 100 located upon the stud shaft 73, utilized for driving the screw 18. Under this arrangement the conveyor has the residue removed therefrom by the ejector device 92 and is also, by means of such ejector device, flattened out and subsequently cleaned by the rotary brush prior to passing over the idler pulley 78.

For assisting in the extraction of the liquid from the liquid yielding materials during the pressing operations, I may spray any suitable liquid upon the material as it is carried within the conveyor and may also spray suitable liquid or solvent upon the conveyor itself as it is drawn between the two pairs of pressing units. For this purpose I provide a supply pipe 101 which may be brought from any suitable source of liquid supply. The lower end of this pipe is provided with an elongated nozzle 102 which is positioned to deliver liquid upon the material within the conveyor as it moves between the top pressing unit 19 and top pressing unit 21. Leading from the supply pipe 101 are oppositely directed branch pipes 103-103 which communicate with pipes 104-104 extending along opposite sides of the conveyor's path just below the pressing unit 19. Also the branch pipes 103-103 communicate with rearwardly extending pipes 105-105 which are located on opposite sides of the conveyor's path just below the top pressing unit 21. The pipes 104-104 and 105-105 are suitably apertured as at 106 in order that the liquid may be sprayed upon the conveyor during the pressing operations. Provision is thus made for introducing liquid into the conveyor as the latter moves along and also for spraying the conveyor during the pressing operation. Supply pipe 101 is supplied with a control valve 107, while the branch pipes 103-103 are provided with control valves 108.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. In a power press, a driven shaft carrying sprocket wheels; a second shaft carrying sprocket wheels; endless chains connecting the sprocket wheels of said shafts and carrying cross strips; and bearing bridges

for said cross strips arranged upon and connecting said shafts, substantially as described.

2. In a power press, a pair of shafts, each mounted in vertically adjustable bearing blocks; wheel means carried by said shafts and endless driving means connecting said wheel means; cross strips connecting said endless driving means; and bearing bridges for said cross strips mounted upon and connecting said shafts to allow relative adjustment thereof, said bearing bridges being arranged on opposite sides of said wheel means, substantially as described.

3. A power press including upper and lower pressing units, each consisting of a pair of shafts with wheel means carrying endless pressing means, the upper pressing unit being of less extent than the lower unit to exert pressure on the upper run of the lower unit between the points of support afforded by its wheel means; bearing bridges arranged on and connecting the shafts of the upper unit for supporting the endless pressing means of that unit; and bearing bridges for the upper run of the endless pressing means of the lower unit arranged for adjustment toward and away from the bearing bridges of the first unit.

4. A power press including upper and lower pressing units, each consisting of a pair of shafts with wheel means carrying end-

less pressing means, the upper pressing unit being of less extent than the lower unit to exert pressure on the upper run of the lower unit between the points of support afforded by its wheel means; bearing bridges arranged on and connecting the shafts of the upper unit for supporting the endless pressing means of that unit; and bearing bridges for the upper run of the endless pressing means of the lower unit, cross bars supporting said bridges and upwardly extending adjusting screws impinging against said cross bars for adjusting the bridges with relation to the upper element, substantially as described.

5. In a device of the class described, an endless belt conveyor, means for feeding material upon said conveyor and a conveyor shaper comprising an outer casing having a bottom and side walls and a former arranged within the casing, also having a bottom and side walls spaced from the corresponding portion of the casing to receive the conveyor, the bottoms of said casing and former being tapered toward the material feeding means and the side walls thereof sloping upwardly and inwardly and progressively increasing in height toward the material feeding means, substantially as described.

In testimony whereof I have signed my name to this specification.

CHARLES KERR.
